UNITED STATES PATENT OFFICE.

DAVID W. GREENE, OF NEW YORK, N. Y., ASSIGNOR TO MAX E. BERNHARDT, OF NEW YORK, N. Y.

CIGARETTE CASE.

Application filed April 30, 1923. Serial No. 27,098.

This invention relates to a cigarette case.

An object of the invention is to provide a cigarette case which can be stamped with one die from one piece of leather or similar fabric or from tin or other metal, and when formed is adapted to provide a case for cigarettes as well as a holder for the cigar lighter and portable lamp.

Another object concerns the provision of simple and efficient means whereby cigarettes can be more efficiently held compactly within a case and dispensed therefrom.

A still further object concerns the provision of simple and efficient means whereby 15 means forming part of the cigarette case will co-operate with the lighter element to prevent the striker from falling out of place.

The invention is illustrated in the drawings, of which—

20 Figure 1 is a perspective view of the combination;

Fig. 2 is a section on the line 2—2 of Fig. 1;

25 Fig. 3 is a section on the line 3—3 of Fig. 1;

Fig. 4 is a partial perspective view of the cover flap;

Fig. 5 is a perspective view of the metal lining for the casing; and

30 Fig. 6 is a plan view of the blank of the container.

The form of the invention shown in the drawings is a preferred form, although it is understood that modifications in the construction and arrangement of the parts and in the character of the materials used may be adopted without departing from the spirit of the invention as set forth in the appended claims.

40 In general this invention includes a cigarette case made of one piece of leather or fabric or metal. This blank is provided with an extension which is bent down over one face of the blank and spaced therefrom to form a chamber for the receipt of a portable lighter which can be slipped therein. The blank is also provided with another extension which acts as a flap and cover for the top of the cigarette case and is then bent down along the front of the case to, preferably, embrace the edges of the lighter and also the striker therefor to prevent it from falling out.

This cover flap is preferably apertured

so as to permit the front of the lighter to 55 be exposed even when the flap is in position and closed.

The container is also provided with a metal lining adapted to hold a cigarette pack from being crushed as the cigarettes 60 are taken therefrom. This lining is also provided with means at the bottom to hold the pack in position, and a portion of the lining at the top is cut away to expose the 65 top of some of the cigarettes so as to enable the smoker to remove them more easily.

In the preferred form of the invention I provide a blank, preferably of leather, although it may be made of other material. This blank is provided with a rear portion 70 10, a front portion 11 and co-operating connecting portions. The rear portion 10 at the top is provided with a flap 12 which extends down along the front of the front portion 11. This flap is connected to the 75 rear portion 10 by a cover portion 13. The flap 12 is apertured as at 14 for a purpose hereinafter to be described. The front portion 11 is provided with an extension or flap 15 which is adapted to be bent down along 80 the front thereof and spaced therefrom. The lower end of this flap can be sewed or otherwise fastened to the front wall 11 and provides therewith a chamber for the receipt of a metal cigarette lighter 16.

85 This lighter is preferably a metal container in which suitable inflammable liquid is contained. This liquid is preferably benzine or gasoline and is held therein by being absorbed in a fibrous material such as 17. 90 The bottom of the igniter is provided with an aperture through which a stem 18 projects. The stem has a handle or knob 19 on its lower end. The stem is the lighter and striker and at its upper end 20 is provided 95 with material which when rubbed along the igniting surface or stone such as 21 will cause the ignition of the inflammable liquid to enable the smoker to light the cigar or cigarette. The striker stone is held in position on the face of the igniter by being placed in a groove or slot therein. Preferably the flap 15 is provided with a slot 22 which registers with the location of the stone and, as shown in Fig. 1, is provided with a metal edging 23 which stiffens the flap and also enables the stone 21 to be held in place. 100 It is easy to see that the cigar lighter 16 105

can be slid in between the flap 15 and the front wall 11 of the cigarette case and can as easily be slid thereout.

This igniter or lighter is so disposed that 5 the striker stem or head 19 extends downwardly away from the top of the casing so that danger of setting fire to the cigarettes or cigars is minimized.

The flap 12 which forms the cover is 10 adapted, as shown in Fig. 1, to extend downwardly across the front of the case, the portion 13 acting as a cover for the top of the case and the opening 14 permitting the exposure of the igniter 16 and the flap 15.

15 The lower end of the flap 12 is provided with a metal finger 24 which is bent inwardly, and as the flap is moved into the position shown in Fig. 1 will lie beneath the head 19 of the striker 18 to prevent the 20 striker from falling out of the igniter.

Preferably the aperture 14 is provided with a metal lining or edging 25 which will reinforce the edges of the flap adjacent the opening and prevent them from curling up.

25 This flap will also prevent the lighter from slipping out from between the flap 15 and the front wall 11.

The case is provided with a metal lining 26 in the form of a sheet bent as shown in 30 Fig. 5. One edge of the bottom of this sheet is provided with a flange portion 27 which will project under the bottom of the cigarette package to hold it in position. One portion of the upper edge of this sheet, as 35 shown at 28, is cut away so that the upper ends of certain of the cigarettes are exposed to permit their ready withdrawal from the case. This cut-away portion also permits the upper portion of the cigarette pack to be 40 torn off to expose the cigarettes therewithin.

In the general construction of the invention, therefore, it is obvious that practically the entire device can be made out of one sheet of material. The flap 15 acts as a 45 container for the lighter. The flap 12 acts as a cover and as a means to hold the lighter in position and to prevent the striker there-

of from falling out. The igniting surface 21 can be loosely disposed on the face of the lighter 16 and will be held in position by the 50 metal edging 23 of the slot 22. The lining 26 within the case will protect the cigarette pack and provide a means whereby the upper portion can be torn off easily to expose the cigarettes and hold the pack in position 55 therein and will also act as a more or less firm base for the action of the striker stem when the smoker is attempting to make a light.

What I claim is:—

1. A cigarette case having its front and rear walls formed integrally with a flap extending from the edge of each wall, one of said flaps adapted to be bent down along the face of the front wall to form a pocket projecting therefrom for a lighter easing, the other of said flaps being provided with an aperture and adapted to be bent down over the top of the cigarette case and along the front wall thereof with the said pocket projecting into the aperture. 60

2. A cigarette case having a flap projecting from its front wall, said flap being bent outwardly, then downwardly parallel and in spaced relation to the front wall and then 70 inwardly and secured at its end only to said wall, and an apertured flap on the rear wall bent down over the top of the case and along the front wall of the case with the pocket projecting through the aperture thereof. 75

3. A cigarette case having a flap projecting from its front wall, said flap being bent down along the front wall of the case and its lower end only secured to the wall, the intermediate portion of the flap being parallel with the wall and spaced therefrom to form a pocket and a flap projecting from the rear wall of the case and extending over the top and front wall of the case, said flap being provided with an opening having a 80 metal lining and through which the pocket projects. 85

DAVID W. GREENE.
